United States Patent Office

Des. 207,460
Patented Apr. 18, 1967

207,460

SUNGLASS FRONT

Louis De Migastris, Providence, and John Paliotta, Cranston, R.I., assignors to Loupal Originals, Inc., Providence, R.I., a corporation of Rhode Island

Filed May 23, 1966, Ser. No. 2,386

Term of patent 14 years

(Cl. D57—1)

FIG. 1

FIG. 2

FIG. 3

FIG. 4

FIG. 1 is a front elevational view showing our new design of a sunglass front;

FIG. 2 is a top plan view thereof;

FIG. 3 is a side elevational view thereof; and
FIG. 4 is a bottom plan view thereof.

The broken lines shown on the drawing are for illustrative purposes only.

We claim:

The ornamental design for a sunglass front, substantially as shown and described.
